US00D462955S

(12) **United States Design Patent**
Van Note et al.

(10) Patent No.: **US D462,955 S**
(45) Date of Patent: ** Sep. 17, 2002

(54) **WIRELESS PROCESSOR-BASED SYSTEM**

(75) Inventors: **Paul C. Van Note**, Portland, OR (US); **Monesh S. Chokshi**, Beaverton, OR (US); **Daniel G. Schkolnik**, Portland, OR (US); **Christopher Loew**, Palo Alto, CA (US); **Markus Diebel**, San Francisco, CA (US)

(73) Assignee: **Intel Corporation**, Santa Clara, CA (US)

(**) Term: **14 Years**

(21) Appl. No.: **29/140,173**

(22) Filed: **Apr. 13, 2001**

(51) LOC (7) Cl. **14-02**

(52) U.S. Cl. **D14/315**

(57) **CLAIM**

The ornamental design for the wireless processor-based system, as shown and described.

DESCRIPTION

FIG. 1 is a top plan view of a wireless processor-based system;

FIG. 2 is a right side elevational view and the left side elevation view is a mirror image;

FIG. 3 is a bottom plan view thereof;

FIG. 4 is a back elevational view thereof; and,

FIG. 5 is a front elevational view thereof.

The broken lines are shown in the view for illustrative purposes only and form no part of the claimed design.
